[57] CLAIM

The ornamental design for a terminal housing for industrial thermometer, as shown and described.

DESCRIPTION

FIG. 1 is a top plan view of a terminal housing for industrial thermometer showing my new design;

FIG. 2 is a right side elevational view, the left side elevational view being a mirror image;

FIG. 3 is a bottom plan view; and,

FIG. 4 is a front elevational view thereof.

FIG. 1.

FIG. 2.

FIG. 3.

FIG. 4.
